FIG. 1.

Fig. 5.

INVENTOR,
August T. Jones
by his attorney,

Charles J. Gooding.

UNITED STATES PATENT OFFICE.

AUGUST IVAR JOHNSON, OF MEDFORD, MASSACHUSETTS.

OILING SYSTEM FOR AUTOMOBILES.

1,396,959.

Specification of Letters Patent. Patented Nov. 15, 1921.

Application filed June 9, 1920. Serial No. 387,562.

To all whom it may concern:

Be it known that I, AUGUST I. JOHNSON, a citizen of the United States, residing at Medford, in the county of Middlesex and 5 State of Massachusetts, have invented new and useful Improvements in Oiling Systems for Automobiles, of which the following is a specification.

This invention relates to an improved 10 crank case and lower cover therefor, the same being particularly adapted for use in Ford automobiles.

In such automobiles the crank case is provided with a cover on the bottom thereof, 15 said cover having three recesses or chambers therein constituting splash cups, spaced apart and in alinement with three of the cranks of the crank shaft, so that as the crank rotates these cranks project into the 20 chambers while passing through the lower arc of their movement and thus distribute the oil.

The oil which is supplied to said chambers is carried from an oil reservoir by the fly- 25 wheel of the magneto located at the rear of the crank case and is delivered by said wheel to a pipe which is inclined downwardly toward the front of the crank case and which delivers the oil to the crank case at the front 30 end. The oil passes into the first of said chambers in alinement with one of said cranks and said crank passes through said chamber and splashes a portion of the oil out of the chamber and over into the second 35 chamber and from the second chamber it is in like manner fed or carried over to the third chamber and from the third chamber it is in like manner carried over into the oil reservoir.

40 It has been found in practice that this method of distributing the oil is defective in that the first chamber referred to may be full of oil while the second chamber has less oil than the first and the third chamber has 45 less oil than the second and it is therefore the object of this invention to provide a construction whereby the oil will stand at substantially the same level in each of said chambers and, furthermore, it is the object 50 of this invention to provide a means whereby the height of the oil in said chambers may be regulated. By these means the uneven amount and over abundance of oil supply at the front of the crank case is carried to the other chambers and the amount 55 of oil supplied to each connection rod is

thus equalized by taking the oil away from the front chamber and supplying it to the other two chambers in equal amounts.

To these ends the invention consists in the 60 improved crank case lower cover set forth in the following specification and particularly pointed out in the claims.

Referring to the drawings:

Figure 1 is a sectional elevation of a portion of a crank case with my improved crank case lower cover attached thereto, the fly-wheel and the oil distributing pipe being shown in dotted lines in connection therewith.

Fig. 2 is an underneath plan of the same.

Fig. 3 is a top plan of the lower cover.

Fig. 4 is a sectional elevation taken on line 4—4, Fig. 2.

Fig. 5 is a detailed sectional plan of the 75 device for regulating the height of the oil taken on line 5—5, Fig. 4.

Fig. 6 is an enlarged sectional elevation taken on line 6—6, Fig. 4.

Like numerals refer to like parts throughout the several views of the drawings.

In the drawings, 10 is the crank case. 11 is a cover fast to the bottom of said crank case and provided with splash cups or chambers 12, 13 and 14. 15 is the oil reservoir 85 into which the magneto fly-wheel 16 projects and carries oil therefrom upwardly delivering the same to a pipe 17, which is inclined downwardly and delivers the oil at the front end of the crank case where it runs 90 into the chamber 12. The chamber 12 is provided in the bottom thereof with a plurality of holes 18 which lead into a conduit 19 extending longitudinally along the bottom of the crank case cover 11, the same being connected by holes 20 and 21 to the chambers 13 and 14 respectively. The conduit 19 has a branch 22 which extends at right angles to the conduit 19 and which has an outlet 23 into which is screwed a hollow 100 plug 24. The plug 24 is provided with a hexagon head 25 and projects through a T-shaped connection 26 which has an annular chamber 27 therein which opens into a passage 28 in the branch 29 of said T-shaped connection. The plug 24 has outlet ports 30 oppositely disposed and leading from the interior 31 of said plug into the annular chamber 27, whereby said outlet ports connect said conduit to said annular chamber 110 27 and passage 28.

The branch 22 of the conduit 19 has an

upwardly extending projection 32 in which is located the outlet 23 and between the upper end of said projection, see Figs. 4 and 6, and the T-shaped connection 26 is located a washer 33. By screwing down from the stud 24 the parts 26, 32 and 33 are firmly clamped together.

It is evident that the height of the oil in the different chambers 12, 13 and 14 will be regulated by the height of the ports 30 and to enable the height of said ports to be varied washers of different thicknesses or a plurality of washers may be interposed between the projection 32 and the connection 26. The connection 26 is connected by a union 34 to an outlet pipe 35 which leads into an elbow 36 to which it is connected by a union 37, the elbow 36 leading into the bottom of the oil reservoir 15.

The general operation of the device hereinbefore described is as follows: Oil is carried upwardly from the reservoir 15 by the fly-wheel 16 and delivered to the pipe 17 by which it is conducted to the forward end of the crank case 10. It then flows downwardly into the chamber 12 and from the chamber 12 it flows through the holes 18 into the conduit 19 and from the conduit 19 through the holes 20 and 21 it flows into the chambers 13 and 14.

The height of the oil is kept the same in the chambers 12, 13 and 14 by means of the branch 22 and plug 24, the oil flowing from the branch 22 through the interior port 31 of the plug 24 and outwardly through the ports 30 into the outlet pipe 35, whence it returns through the elbow 36 to the reservoir 15.

I claim:

1. A crank case for automobiles having a plurality of chambers for oil in the bottom thereof, a reservoir for oil, a rotary member adapted to project into said reservoir, a pipe leading downwardly from said rotary member to one of said chambers, whereby oil may be fed from said reservoir to said last-named chamber, a supply conduit opening into the bottom of each of said chambers and connecting them to each other and an overflow pipe extending upwardly from said conduit above said chambers and thence downwardly to said reservoir.

2. A crank case for automobiles having a plurality of chambers for oil in the bottom thereof, a reservoir for oil, a rotary member adapted to project into said reservoir, a pipe leading downwardly from said rotary member to one of said chambers, whereby oil may be fed from said reservoir to said last-named chamber, a supply conduit opening into the bottom of each of said chambers and con-

necting them to each other, an overflow pipe extending upwardly from said conduit above said chambers and thence downwardly to said reservoir and means in said overflow pipe adapted to regulate the level of oil in said chambers.

3. A crank case for automobiles having a plurality of chambers for oil in the bottom thereof and having a reservoir for oil, a conduit opening into each of said chambers and connecting them to each other, an overflow pipe leading from said conduit to said reservoir, there being an outlet port leading from said conduit into said overflow pipe, and means to adjust the level of the bottom of said port vertically, whereby the level of the oil in said chambers may be regulated.

4. A crank case for automobiles having a plurality of chambers for oil in the bottom thereof and having a reservoir for oil, a conduit opening into each of said chambers and connecting them to each other, an overflow pipe opening at one end thereof into said reservoir, a connection attached to the opposite end of said overflow pipe and provided with an annular chamber, a hollow plug connecting said last-named connection to said conduit, said plug being provided with an outlet port leading from the interior thereof into said annular chamber and having screw-threaded connection with said conduit, whereby said connection may be clamped to said conduit.

5. A crank case for automobiles having a plurality of chambers for oil in the bottom thereof and having a reservoir for oil, a conduit opening into each of said chambers and connecting them to each other, an overflow pipe opening at one end thereof into said reservoir, a connection attached to the opposite end of said overflow pipe and provided with an annular chamber, a hollow plug connecting said last-named connection to said conduit, said plug being provided with an outlet port leading from the interior thereof into said annular chamber and having screw-threaded connection with said conduit, whereby said connection may be clamped to said conduit, and a washer interposed between said connection and said conduit, whereby the level of the bottom of said port may be adjusted vertically and the level of the oil in said chambers may be regulated.

In testimony whereof I have hereunto set my hand in presence of two subscribing witnesses.

AUGUST IVAR JOHNSON.
